UNITED STATES PATENT OFFICE.

JOHN A. KROPP, OF NEWARK, NEW JERSEY, ASSIGNOR TO WESTERN ELECTRIC COMPANY, OF NEW YORK, N. Y., A CORPORATION OF ILLINOIS.

SENDER.

1,124,751.

Specification of Letters Patent.

Patented Jan. 12, 1915.

Application filed September 25, 1913. Serial No. 791,770.

To all whom it may concern:

Be it known that I, JOHN A. KROPP, a citizen of the United States, residing at Newark, in the county of Essex and State of New Jersey, have invented a certain new and useful Improvement in Senders, of which the following is a full, clear, concise, and exact description.

My invention relates to improvements in 10 substation senders used in connection with an automatic telephone system to send a series of current impulses to a central office, and in which each series of impulses corresponds to a digit in the subscriber's number 15 wanted by the calling subscriber. Its principal object is to provide an improved apparatus which will make manipulations by the subscriber simple in movement, and rapid in succession and the sending of impulses 20 positively accurate. I provide for that purpose a handle adapted by a rotary movement followed by a rocking or longitudinal movement to operate a circuit interrupting mechanism which transmits a 25 number of impulses for each digit selected, the number of impulses transmitted in each case depending on the corresponding angular distance covered by the handle in its rotation from a normal position. I provide also a locking mechanism which is 30 adapted to detain the handle in operative position between each selection of digits, but this detention is only long enough to 35 allow the proper transmission of impulses, thereby preventing the subscriber from improper manipulation of the apparatus.

My invention will be particularly described, and the various features thereof explained in detail by referring to the accompanying drawings in which—

Figure 1 is a perspective view of the mechanism with part of front cover and locking mechanism broken away. Fig. 2 is a front elevation of the mechanism with approximately the same parts removed as in Fig. 1. Fig. 3 is a side sectional view of the mechanism taken on line 3—3 of Fig. 2. Fig. 4 is an elevation of the mechanism looking from the back. Fig. 5 is a sectional view taken on the line 5—5 of Fig. 3 and looking from the back of the mechanism. Fig. 6 is a partial sectional view of the handle and its most intimately associated parts. Fig. 7 is an enlarged fragmentary 50 perspective view of the handle locking

mechanism. Fig. 8 is a perspective view of the impulse sending switch mechanism.

The same letters of reference are used to designate the same parts wherever they are shown.

Referring now more particularly to Figs. 1, 2, 3, 5, 6 and 7, the operation of the mechanism is controlled by the rotation and locking of a handle 9 having an operating knob 10 secured to one end thereof and the other end affixed to a shaft 11. This shaft is pivotally mounted in a bearing 12 which is shaped so as to allow a rocking movement of the shaft using the pivot 13 as a fulcrum. The bearing 12 is in turn mounted rotatably 70 in another bearing 14 and is held in place by means of the cap nut 15 which also serves to clamp the bearing 14 to the front cover or dial plate 16.

Secured to the inside end of the shaft 11 75 is a crank lever 17 having mounted on its free end a spring actuated latch or pawl 18, the purpose of which will hereinafter be described. The handle 9 and crank lever 17 are mounted so as to point in opposite directions and are normally held in a parallel position with regard to the dial plate by means of a spring 19 mounted in the bearing 12 and having its free end engaging the under surface of the handle 9. If the handle is rotated in a clockwise direction from its normal position (shown in Fig. 2) for the selection of a particular digit and placed in front of any one of the apertures 20 designated from 0 to 9 inclusive as shown 90 on dial plate 16, then depressed so that the latch 21 on the extreme free end thereof enters an aperture 20, it will be locked therein by means of a locking plate 22 having an aperture 23 registering with each of the 95 apertures 20. The apertures 23 are for that purpose each provided with a lip or projection 24 extending partly in the path of the latch 21. When the handle is depressed, a slanting plane on the end of the latch engages the lip 24 and moves the locking plate 22 to one side until the notch 25 cut in the side of the latch registers with the locking plate when the latter slides back to the position it held before being moved by the 100 latch and thereby locks the handle in its depressed position. In the normal condition 105 of the sender mechanism, the locking plate 22 is held in its non-locking position by means hereinafter described; but when said 110

mechanism is moved from normal by turning of the handle 9, said locking plate is moved to its locking position by springs 27, and remains yieldingly held there until the 10 sender mechanism returns to normal. One end of these springs is attached to the locking plate and the other to the sides of the front cover or dial plate 16, the locking plate being slidably mounted on the under 15 surface of the dial plate by means of rivets and guide bolts. The winding mechanism which is set and released by these two controlling movements of the handle will now be described. The actuating latch or pawl 18 on the crank lever 17 engages the notch 28 on an arm 29 which thereby is forced to participate in the rotary movement of the handle until the pawl 18 releases it by being thrown out of alinement with the arm 20 through the rocking movement of the crank lever 17 caused by the depression of the knob 10. This rocking movement is illustrated very clearly in Fig. 6. The arm 29 is attached to one end of a shaft 30, the 25 other end of which is slit in the center to receive the inside end of a spiral spring 31 having its outer end secured to the side of a projecting casing or shell 32, which in turn is secured rigidly to a bracket 33 fastened to the bottom supporting plate 34.

The impulse sending mechanism consists of a series of spring contact members 35, 36, and 37. Spring 37 is adapted through the medium of an insulating knob 38 to break 35 the connection between springs 35 and 36 which are connected to the wires of the substation circuit leading to the central office. A toothed wheel 39 is adapted in its rotation to operate spring 37 once for each tooth, 40 that is, to break the connection between springs 35 and 36. This toothed wheel 39 is mounted on a sleeve 40 running loose on shaft 30 and moved by a ratchet wheel 41 mounted on the other end thereof, said 45 ratchet wheel being engaged by a pawl 42 attached to the arm 29. The toothed wheel 39 may therefore be rotated a definite number of stops depending on the angular displacement of the arm 29, which depends entirely on how far from its normal position 50 it has been moved by the handle and crank lever. A definite number of impulses may be sent over the line by breaking the connection between the springs 35 and 36 a corresponding number of times; and the parts 55 are so proportioned that the number of impulses to be used in each case are indicated on the dial plate adjacent to the different positions in which the handle may be placed.

60 A governing mechanism for the regulation of the speed at which these impulses may be sent is provided, consisting of a gear wheel 43, affixed to and participating in the movements of the sleeve 40, engaging a pinion 44 which is mounted integrally with a worm

wheel 45 on shaft 46. The worm wheel 45 engages the worm 47 of a governor 48 having weights 49 attached to the free ends of its springs 50. It will be evident that this governing mechanism retards the return 70 movement of the impulse sending mechanism under tension of spring 31.

As hereinbefore mentioned, the handle 9 is locked in the operative position to which it may be advanced, being thereafter released when the mechanism is ready to be operated for the sending of the second series of impulses for the selection of another digit. This releasing of the handle is brought about by the stop 26 engaging the 80 projection 51 on locking plate 22 and moving it into an unlocking position against the tension of the springs 27 and up against the stop bracket 52 fastened to the dial plate. Stop 26 is for that purpose affixed to 85 the arm 29 and unlocks the handle at the end of the return movement of the arm, thereby making it impossible for the operator to manipulate the mechanism for the sending of a second series of impulses until 90 an interval sufficient for the proper sending of the first series of impulses has elapsed.

A brief summary of the operation is as follows: The handle 9 is rotated in a clockwise direction from the normal position 95 shown in Fig. 2 and placed in front of the aperture 20 of the particular digit wanted, and then depressed so that the latch 21 thereon enters said aperture and a similar aperture 23 in the locking plate 22. The handle when thus depressed is locked by the locking plate 22 by reason of the slanting plane on the latch engaging the lip 24 on the plate and moving it to one side until the notch 25 in the latch 21 registers with the lip 24 when the plate slides back to normal position and locks the handle. When the handle is thus manipulated the actuating pawl 18 on the crank lever 17 engages the arm 29 which thereby is forced to participate in the rotary movement until released by the pawl 18 which is thrown out of alinement therewith by the rocking movement of the handle. The rotation of the arm 29 winds a spring 31 through the medium of the shaft 30, and said arm will therefore when released rotate the impulse-sending wheel 39, by means of the pawl 42 and ratchet wheel 41 attached respectively 100 to the arm and to the sleeve 40 carrying the impulse-sending wheel. The rotation of the wheel 39 causes through the manipulation of the springs 35, 36 and 37 the sending of the selected number of impulses over the line. The stop 26 will, when the arm 29 is 105 near the end of its return journey to normal, shift the locking plate sufficiently to unlock the handle, allowing the same to return to normal position in readiness for 110

115 another operation.

It is obvious that many modifications, rearrangement of parts and changes in detailed construction could readily be made in this particular embodiment of my invention without departing from the spirit thereof.

I claim:

1. In a sender, the combination with a circuit interrupter, of an actuating member therefor capable of a rotary and rocking movement, means adapted to clutch said circuit interrupter and cause it to operate, and depending for such actions on a rotary, followed by a rocking movement of said actuating member.

2. In a sender, the combination with a circuit interrupter, of a handle, a shaft, a crank lever connected to said handle by means of said shaft, means adapted to actuate said circuit interrupter and depending for its actions on a rotary movement followed by a rocking movement of the crank lever.

3. In a sender, the combination with a circuit interrupter, of a handle, a crank lever, a shaft connecting said handle and crank lever, a bearing in which said shaft is pivotally mounted in such a way as to permit of a rocking movement of the shaft by the manipulation of the handle, a second bearing in which said first bearing is mounted permitting of a rotary movement thereof in said second bearing by the manipulation of the handle, and means by which a rotary followed by a rocking movement of said handle and crank lever will actuate said circuit interrupter.

4. In a sender, the combination with a circuit interrupter, of an actuating member therefor, a motor mechanism, means for storing up of energy in said motor mechanism, said means depending for its action on a rotary movement of the actuating member, means for releasing said motor mechanism to cause the operation of said circuit interrupter, said means depending in its action on a rocking movement of the operating member.

5. In a sender, the combination with a circuit interrupter, of an actuating member therefor, a spring, an arm associated with said spring by means of a shaft, means on said actuating member for rotating said arm to store up energy in said spring, a pawl on said arm for actively engaging said circuit interrupter, and means on said actuating member for releasing said arm to cause it under tension of the spring to operate said circuit interrupter, said means depending for its operation on a rocking movement of the actuating member.

6. In a sender, the combination with a circuit interrupter, of an actuating member, a motor mechanism for the operation of said circuit interrupter, means for coupling said actuating member to said motor mechanism

when the member is moved in a rotary direction, and means for releasing said member from said motor mechanism when the member is given a rocking movement.

7. In a sender, the combination with a circuit interrupter, of a motor mechanism for the actuation of said circuit interrupter to cause it to send a predetermined number of impulses over a line, an actuating member adapted by a rotary movement to store up energy in said motor mechanism, and by a rocking movement to release said motor mechanism, means for locking said actuating member in its advanced rotated position by a rocking movement thereof until said interrupter has sent all of the impulses, and means for thereafter releasing said actuating member allowing it to return to normal position by its own weight.

8. In a sender, the combination with a circuit interrupter, of a motor mechanism therefor, an arm co-operating with said motor mechanism, an actuating member for the operation of said arm to store up energy in said motor mechanism, a pawl on said arm for coupling it to the circuit interrupter when said arm is in an operated position, said arm during its return journey to normal adapted to actuate said circuit interrupter to send a predetermined number of impulses, a latch plate, a latch on said actuating member adapted through a rocking movement thereof to be locked by said plate in an operated position, a pin on said arm for releasing of said actuating member by active engagement with said plate; said releasing action taking place immediately after the arm in its journey back to normal has caused the circuit interrupter to send all of the predetermined number of impulses.

9. In a sender, the combination with a circuit interrupter, of a motor mechanism, an actuating member capable of a rotary movement followed by a rocking movement and adapted by said movements to actuate said motor mechanism to cause it to actively engage said circuit interrupter for the purpose of sending of impulses, and a speed governing mechanism for said motor mechanism.

10. In a sender, the combination with a circuit interrupter, of an actuating member therefor, means for selecting a varying number of impulses to be sent by said circuit interrupter, said means depending for such selecting action on a varying rotary movement of the actuating member, and means for releasing said circuit interrupter, for sending of the impulses selected, said means depending for its action on a rocking movement of the actuating member.

11. In a sender, the combination with a circuit interrupter, of an operating member therefor, a spring actuated arm adapted to

be rotated by a varying rotary movement of said actuating member in a position to engage the circuit interrupter for the transmission of a different number of impulses depending in each case on the extent of the angular displacement of the arm from a normal position, a clutch device on said actuating member adapted by a rocking movement of said member to release said arm allowing it to return to normal position, another clutch device coöperating with said arm and adapted to actively engage the

circuit interrupter, during the return movement of said arm to normal position, thereby sending the predetermined number of 15 impulses previously selected.

In witness whereof, I hereunto subscribe my name this 22d day of September, A. D., 1913.

JOHN A. KROPP.
